(57) **CLAIM**

We claim the ornamental design for a box with roll of bags, as shown and described.

DESCRIPTION

FIG. 1 is a perspective view of a box with roll of bags according to a first embodiment showing our new design;

FIG. 2 is a front view thereof;

FIG. 3 is a right side view thereof;

FIG. 4 is a left side view thereof;

FIG. 5 is a top plan view thereof;

FIG. 6 is a bottom plan view thereof;

FIG. 7 is a rear view thereof;

FIG. 8 is a perspective view of the box with roll of bags according to a second embodiment showing our new design;

FIG. 9 is a front view thereof;

FIG. 10 is a right side view thereof;

FIG. 11 is a left side view thereof;

FIG. 12 is a top plan view thereof;

FIG. 13 is a bottom plan thereof; and,

FIG. 14 is a rear view thereof.

The broken lines shown represent unclaimed subject matter and form no part of the claimed design.
